Elias E. Ries

UNITED STATES PATENT OFFICE.

ELIAS ELKAN RIES, OF NEW YORK, N. Y.

SUSPENSION-HOOK FOR BOOTS AND SHOES.

SPECIFICATION forming part of Letters Patent No. 283,418, dated August 21, 1883.

Application filed May 9, 1883. (No model.)

To all whom it may concern:

Be it known that I, ELIAS E. RIES, a citizen of the United States, residing at New York, in the county and State of New York, have invented certain new and useful Improvements 5 in Combined Coupling and Suspension Hooks for Boots and Shoes, of which the following is a specification.

My invention relates to improvements in devices for fastening boots and shoes and analogous articles in pairs, so that they may be suspended from hooks or nails in the ceiling or walls of a store, or from hooks, wires, or rods in a show-window, in such manner that the 10 boots or shoes may be readily taken apart for exhibiting, fitting on, or any other purpose, and as readily again connected, and that they may be easily and quickly taken from and restored to the hooks or rods upon which they 15 belong. I accomplish this by means of wire coupling-hooks, which hooks are variously formed, according to the requirements of the particular kind of goods they are intended for, as will be more fully described hereinafter.

20 Heretofore boots and shoes have been connected in pairs by means of a string or cord connecting them, and have usually been placed in show-windows or suspended from the ceiling or walls of a store so connected; thus making it difficult to convey them to and from their 25 places and entailing a great loss of time in reconnecting them after being cut apart for "trying on," &c., while the strings are seldom of the same length, and therefore give an uneven 30 appearance to the boots and shoes.

The object of my invention is, first, to provide a simple and durable coupling device for coupling a pair of boots or shoes, so that they 35 may be easily and quickly coupled or uncoupled without in any manner wrinkling them, and in such a way that the boots or shoes will, when suspended, hang at the same distance and present a uniform and even appearance; second, to provide means for rapidly lifting to 40 and suspending the boots and shoes so connected from rods or hooks in a show-window or ceiling of a store; third, to provide means for holding and displaying a price or show card in connection therewith; and I attain 45 these objects by means of peculiar shaped wire

hooks, which hooks are so constructed that one or both of a pair of boots or shoes may be rapidly and easily connected or disconnected without disturbing the other, and at the same time allow them to be readily lifted to or from 55 their supporting hook or nail by means of a hooked stick or otherwise.

My invention consists of a combined coupling and suspension hook made of one piece of wire, of iron, brass, or other suitable metal, 60 which wire is so formed or bent at its respective ends as to form hooks or horizontal supports for the straps of a pair of boots or shoes; and the invention further consists in the combination therewith of inclined or converging 65 sides with a ring or loop formed by a twist in the wire, so that a hooked stick introduced anywhere between the inclined sides will be guided directly to a point under the ring or loop, thereby permitting the hook, with its pair 70 of boots or shoes or other articles, to be readily lifted in such a manner that the ring or loop is left free and unobstructed to engage with a nail or hook destined to receive and support it.

The invention consists, further, in forming 75 the hooks intended for displaying goods in show-windows, &c., with a double or slotted ring, in order to allow of inserting a price-card, label, or other mark, so as to be firmly held 80 between the double ring or in the slot.

In the drawings accompanying this specification, Figure 1 is a vertical elevation in perspective of the hook used for boots and shoes having their straps on the side. Fig. 2 is a vertical side elevation of the same. Fig. 3 is 85 a top view of the same hook. Fig. 4 is a vertical elevation of the hook used for boots and shoes having straps in the front and back, and Fig. 5 is a vertical end view of the same on line y y, Fig. 4. Fig. 6 is a perspective view 90 of a modified form of the hook designed for buttoned boots or shoes. Fig. 7 is a detailed view in perspective of the hook when formed with a double ring for introducing a show-card, and Fig. 8 is an end view of the same on line z z, Fig. 7. Fig. 9 is an end view of the upper part of the hooks shown in Figs. 4, 5, and 6, showing the ring as it appears when slotted or split for the introduction of a show-card or price-mark. Fig. 10 is a general ele- 95 100

vation in perspective of the hook, showing the manner in which it is used, with shoes and price-card in position.

Similar letters of reference indicate corresponding parts throughout the several views.

As will be seen by reference to the drawings, the hook, although made of one single length of wire, consists of several distinct features, each fulfilling a certain peculiar function in its application, as will be shortly described. These features may be classed into five general divisions or parts of the hook, which are lettered in the drawings as A B, C C, D D, E E, and F F. The wire of which the hook is formed, having been cut to the proper length, is preferably bent at or near its center, so as to form the ring or loop A, then crossed or twisted upon itself one or more times, as shown at B in Figs. 1, 2, and 3, and in Figs. 4, 5, and 6. The free ends of the wire are now inclined outward and downward from their junction at b, as shown at C C, then bent to form the vertical sides D D, then again bent at right angles to D D in order to form the horizontal portions E E, and finally again bent to form the short upright guards, F F. The horizontal parts E E of the hook fit, respectively, into one of the finger-straps of each of the two boots or shoes forming a pair, and are made long enough to hold the straps without wrinkling them. The short upright guards F F effectually prevent the boots or shoes from accidentally slipping or falling off the horizontal coupling-arms E E.

The ring A is intended to engage with ordinary hooks or nails permanently secured to the wall or ceiling of a store or to rods in a show-window, as shown at H, Fig. 10, in section, and this ring A may be made double, as shown at a', Figs. 7 and 8, or may have a longitudinal slot, s, extending partly around it, Fig. 9, for the reception of a show or price card.

The twist B serves to separate the ring A from the lower portion of the hook, to strengthen the lower portion to a great extent against any tendency to spring inward from the weight of boots or shoes, and to act as a support at its lower end, b, for a hooked stick or rod in lifting it to and from its place on the stationary hooks, nails, or rods. In Fig. 1 the twist B is shown single, while in Fig. 4 it is double.

The function of the inclined sides C C is to separate the space between the boots and shoes so they will hang without crowding, and to guide a hooked stick that may be inserted anywhere within the space bounded by the sides C C and D D to the point b at the junction of C C.

The vertical sides D D are used to enlarge the open space above the boots or shoes, and thereby facilitate the insertion of the lifting-stick and assisting the sides C C in guiding the lifting-stick to b, and they also serve in bringing the center of gravity of the hook a little below b, in order that the hook may be lifted at b in an upright position without any load.

In Fig. 1, used for boots and shoes having side straps, (or straps running in the direction of their length,) the inclined sides C C are bent in a backward direction from the ring A, and the horizontal supports E E are formed parallel with each other and at a relative right angle with the face of the ring A, thus bringing the ring A directly over the supporting-arms E E, Figs. 2 and 3, and maintaining the center of gravity from b in such a manner that the arms E E will remain level with or without a load when the hook is lifted or suspended at either the junction b or ring A.

The form of hook shown in Fig. 4 differs from Fig. 1 in having its arms E E bent outward in opposite directions from the upright side D D, and in having all its parts in a vertical line, as shown in the end view, Fig. 5.

In Fig. 6 is shown a hook similar to the one shown in Fig. 4, but having its two extremities bent into hooks G G, for engaging the shank of the upper buttons on buttoned boots or shoes or the upper eyelet-holes on laced shoes.

Fig. 10 represents a hook provided with a slot, s, as shown in Fig. 9, and shows the manner of inserting the price-card J, which in this case has a circular opening corresponding to the opening in the ring A formed in it, as indicated by the dotted line K, in order to leave the ring unobstructed and free to engage with the hook or nail H. This figure also shows the method of coupling a pair of shoes and their appearance when supported on the hook by their front straps.

The invention is intended not only for coupling and displaying finished boots and shoes, but can be used to great advantage during their manufacture in keeping the pairs from becoming separated or mixed during the different operations, preventing the bottoms or uppers from being soiled or scratched by coming in contact with the work-bench, facility for transporting them from place to place in pairs, hanging them safely out of the way when not in immediate use, and for many other purposes.

The combined coupling and suspension hook above described is not limited in its application to boots and shoes alone, but can be used equally well for any other articles requiring to be connected in pairs and supported from hooks or nails in ceilings, walls, show-windows, or other places.

Having thus described my invention, what I claim as new, and desire to secure by Letters Patent of the United States, is—

1. A combined coupling and suspension device for holding boots and shoes, made from a single piece of wire, and consisting of a suspension-ring, A, inclined or converging sides C C, and vertical arms D D, terminating in holding hooks and guards, all arranged substantially as and for the purpose set forth.

2. A suspension device for holding boots and shoes and analogous articles, consisting of the slotted or split suspension ring A, inclined

or converging sides C C, and depending arms D D, terminating in hooks or guards for holding the boots or shoes or other articles, all from a single piece of wire bent to form all the parts, substantially as shown, and for the purpose described.

3. A combined coupling and suspension device for holding a pair of boots or shoes or analogous articles, consisting of a double spiral ring for receiving and holding a show or price card, inclined or converging sides, for guiding a lifting-stick, and depending arms terminating in hooks or guards for coupling and holding the boots or shoes or other articles, all from a single piece of wire, all arranged and constructed to operate substantially as set forth.

4. A combined coupling and suspension device for holding and coupling boots and shoes, made from a single piece of wire, and consisting of the suspension-ring A, inclined sides C C, depending vertical sides D D, and the horizontal coupling-arms E E, for engaging the straps of a pair of boots or shoes, provided with guards for retaining the straps, all arranged substantially as and for the purpose set forth.

In testimony that I claim the foregoing as my invention I have signed my name in presence of two subscribing witnesses.

ELIAS ELKAN RIES.
